UNITED STATES PATENT OFFICE.

RUDOLF WILTS, OF BREMEN, GERMANY.

LUFFING CRANE.

Application filed June 20, 1927, Serial No. 200,219, and in Germany May 7, 1926.

Luffing-cranes with inclined oscillating axle for the jib are known. In luffing-cranes of this type the jib-head oscillates on an elliptic guide bar the fulcrum point of which 5 is the inclined axle. The charge is not swung in a plane from forward to the rear but it describes an elliptic course which is more or less strongly set off in accordance with the angle of inclination of the axle. Cranes of 10 this type cannot work on one hoist opening as has to be done according to the invention.

The invention has for its object to make two cranes work on one ship's hatch to accelerate the loading and discharging of the 15 ships.

According to the invention the jib executes, with regard to the horizontal pivot axis, such a movement that the charge swings laterally 20 parallel along the crane frame.

It has been proposed to construct cranes 25 as slewing cranes.

In combination with a jib having a laterally projecting or set off jib head the application of the oscillability presents the advantage that, when the ship's hatches are not situated accurately on the plane of oscillation 30 of the jib head the charge may be swung along the portal from forward to the rear at an angle to the portal.

Another characteristic feature of the 35 invention is that a luffing crane of the improved construction is constructed as a slewing crane.

An embodiment of the invention is illustrated, by way of example, in the accompanying drawing in which:—

Fig. 1 shows the improved crane in front elevation.

Fig. 2 shows the crane in side elevation in the position prior to the lifting of 40 the load.

The luffing-crane has an oscillatable arm or jib *b* pivotable around a horizontal axle *e*. This jib projects laterally at an angle to the vertical plane of its base or supporting frame *d* and its extremity or tip *b*¹ is offset

at an angle to the arm in the same direction so that, when the jib is oscillating around the axle *e* the load *c* is elevated along the under frame *a* of the crane (portal) at the smallest possible distance. After the load 50 has been elevated up to the hatch-crown the further lifting is effected merely by luffing the jib. On the portal *a* the supporting frame *i* for the crane beam is mounted on a base plate *g* pivotable around a vertical 55 axle *g'*.

The lifting-luffing-and slewing-gear, and the driver's stand are located in the cabin *d*. The jib has, as usual, a counter weight *f*.

The jib may be operated, in any suitable 60 manner, by direct tooth gear drive or by hauling in by means of ropes.

The advantages consist specially in that the load to be lifted is charged and discharged merely by lifting and luffing without rotation of the crane.

I claim:

1. A crane comprising a supporting base, a frame mounted on said base to rotate on a vertical axis, and a crane arm mounted on the frame between the vertical center and one side of the frame to swing on a horizontal transverse axis, the portion of the crane arm above the said horizontal transverse axis being inclined toward its tip at 70 an outward and upward lateral angle toward and beyond the vertical plane of the opposite side of the frame and base, whereby in shifting a load supported from the arm tip by rotation of the arm on the horizontal 75 transverse axis the load will be moved from front to rear or vice versa close to and parallel with the latter-named side of the frame and base.

2. A luffing-crane as specified in claim 1 in 80 which the free end of the crane arm is offset laterally with relation to the offset arm and in the same direction.

In testimony whereof I affix my signature.
RUDOLF WILTS.
